DRAFT RIGGING

Donald S. Barrows, Rochester, N. Y., assignor to
The Symington Company, New York, N. Y.,
a corporation of Maryland

Application April 20, 1931. Serial No. 531,549

6 Claims. (Cl. 213—22)

This invention relates to draft rigging, and more particularly to such employing a plurality of cushioning devices disposed between a backstop or center filler casting and the adjacent end 5 of a railway vehicle, all of said devices being preferably used for absorbing buffing forces, and only part for absorbing draft forces.

The principal object of my invention, generally considered, is to provide a series of draft 10 gears or cushioning devices mounted between the draft sills of a railway vehicle forwardly or outwardly of an associated backstop member, and so connected to an associated coupler that all are actuated when said coupler is subjected to buffing 15 forces, and only one or less than all of said gears is actuated when the coupler is subjected to draft forces.

Another object of my invention is to provide 20 selective travel cushioning mechanism involving three or more units arranged in a series, and associated with a drawbar and connected horizontal yoke in such a way that all of the gears are actuated for absorbing buffing blows, while the intermediate of said gears is actuated for absorbing both draft and buffing forces.

A further object of my invention is the provision 30 of cushioning mechanism involving a series of cushioning units or devices, each device comprising a housing open at one end and receiving friction wedges or blocks urged apart by associated resilient means or springs, said housings being arranged so that they alternately face forwardly and rearwardly.

Other objects and advantages of the invention 35 relating to the particular arrangement and construction of the various parts will become apparent as the description proceeds.

Referring to the drawings illustrating my invention the scope whereof is defined by the appended claims:—

Figure 1 is a vertical longitudinal view of rigging disposed between the sills of a railway vehicle underframe, illustrating one embodiment of my invention, with one of the friction gears 45 or units shown in vertical longitudinal section.

Figure 2 is a partial horizontal sectional view of the mechanism shown in Figure 1, portions of the parts being shown in plan.

Figures 3 and 4 are views corresponding generally to Figures 1 and 2, but showing a modification.

Figure 5 is a transverse sectional view on the line 5—5 of Figure 3, looking in the direction of the arrows.

Figure 6 is a transverse sectional view on the

line 6—6 of Figure 3, looking in the direction of the arrows.

Figures 7 and 8 are fragmentary views corresponding generally to Figures 1 and 2, but showing another modification.

60

Figures 9 and 10 are views corresponding generally to Figures 1 and 2, but showing a further modification.

65

Figure 11 is a fragmentary transverse sectional view on the line 11—11 of Figure 9, looking in the direction of the arrows.

Figures 12 and 13 are fragmentary views corresponding generally to Figures 9 and 10, but showing a modification.

70

Figure 14 is a fragmentary view corresponding generally to Figure 12, but showing another modification.

75

Figure 15 is a fragmentary view corresponding to Figure 14, but showing a further modification.

75

Figure 16 is a fragmentary transverse sectional view of the embodiment shown in Figure 15.

Figure 17 is a fragmentary view corresponding generally to Figure 10, but showing a still further modification.

80

Referring to the drawings in detail, like parts being designated by like reference characters, and first considering the embodiment of my invention illustrated in Figures 1 and 2, there are shown portions of a railway vehicle underframe 85 comprising draft or center sills 1 connected by a backstop or center filler casting 2 and a striking casting or combined striking casting and sill tie member 3. The sills 1 are slotted for receiving draft keys for connection with associated draft rigging, and preferably have connected thereto cheek plates 4 which are correspondingly slotted with the slotted portions therein preferably reinforced by flanges 5 for rigidifying the edges of said members adjacent the slots to provide for the transmission of large forces.

90

In the present instance, the front slots 6 are formed partly in rearward extensions or side portions 7 on the striking casting, and partly in cheek plates 8 which are connected to the sills rearwardly of the extensions 7. The second or rearmost slots 9 are formed in the separate cheek plates 4.

95

Mounted between the sills 1 is a series of cushioning units or gears 10, preferably supported on carry irons 11 and 12, which are, in turn, connected to the sills 1 in any desired manner, as by connecting means or bolts 13. Each gear desirably comprises a housing, friction casing, column member or shell 14 open at one end and formed with a notch or open-ended slot 15 at the closed

100

105

110

end, so that when arranged back to back, like the two outermost gears 14, the open-ended slots 15 cooperate to form a complete or closed slot adapted to receive a supporting or second draft key 16, which is also adapted to function as a front stop for the second gear 10, as the front edge thereof normally contacts with the foremost end of the slots 9 in the cheek plates 4.

The open end of each housing or shell 14 is preferably formed double bell-mouthed, that is, it is provided with sloping walls 17 providing outermost flaring or inclined friction surfaces 18, and inwardly disposed, but preferably correspondingly inclined, friction surfaces 19 with a shouldered portion 20 therebetween. Cooperating with the friction surfaces and shouldered portions on each shell or housing 14 are friction shoes or wedges 21 provided with correspondingly inclined friction surfaces 22 and 23 engaging the corresponding friction surfaces on the shell, and provided with a shouldered portion therebetween for cooperating with the correspondingly shouldered portions on the housing for limiting outward movement of said friction elements with respect to said housing after assembly therewith.

In order to urge the friction elements 21 into engagement with the friction surfaces on the housing 14, resilient means 24, preferably in the form of curved plate springs, are provided between the friction elements in each housing. Said plate springs preferably involve two sets, bowed or curved concavely toward the adjacent friction elements 21. Although only one of the friction devices or gears 10 is shown in section and completely described, it will be understood that all of said gears may be similar and interchangeable, or different, as desired.

The associated two outer gears 10, which cooperate to form a complete slot receiving the key 16 are, in the present embodiment, connected to the drawbar or coupler stem 25 in a usual manner, as by means of yoke-acting means, for example, a horizontal yoke 26 embracing said gears, and associated front and rear followers to be subsequently described, with its arms extending forwardly on each side thereof and connected to the drawbar 25 by a front or outer horizontal draft key 27 extending through registering slots in the yoke and drawbar, and with its ends received in the slots 6 in the cheek plates 8 and rearward extensions 7 of the striking casting 3. The slots 6 are of a length sufficient to permit the key to move distances in both directions sufficient to stress the associated cushioning devices or gears to the desired extent. Although I have illustrated conventionally the drawbar 25 as being the shank or stem of a coupler of the type described and claimed in my Patent No. 1,431,717, dated October 10, 1922, it will be understood that I do not wish to be limited to the use of such a swivel butt coupler in the combination here disclosed.

Disposed between the drawbar 25 and the friction elements 21 of the front gear 10 is a front follower 28 designed to transmit buffing forces from the drawbar to the friction elements 20 to effect compression of the gears 10. In order to hold the follower in proper position with respect to the yoke 26, shoulders or extensions 29 are desirably provided and spaced to receive the yoke arms therebetween, as illustrated particularly in Figure 1. The rear follower 30 is desirably held in position with respect to the yoke by corresponding projections 31, and said followers are

desirably also guided and supported by the carry irons 11 and 12.

In order to increase the permissible travel of the drawbar or coupler stem 25 under the action of buffing forces, as well as provide an increased cushioning action for absorbing such forces without increasing such movement and capacity for draft forces, the third or inner friction gear or device 10 is disposed between the yoke 26 and the buffing wall or face 32 of the backstop 2. This third or innermost gear 10 may be formed identical with, or different from, the other gears 10 and be provided with a front follower 33 disposed between the yoke and the friction wedges 21 of said gear. The carry iron 12 is preferably extended rearwardly an amount sufficient to support the front edge of the open end of the housing 14 for said rear gear, the rear end of said housing being desirably supported by a bottom cover plate or member 34 disposed beneath the sills and backstop 2. In order to provide for transmitting buffing forces from the follower 33 directly to the sills without overloading the housing 14, rear stop lug members 35 are desirably provided and disposed on either side of the housing 14, said members being desirably connected to the webs of the sills 1 by rivets 36, or the like, in such a position that they either receive all the overload buffing forces from the floating follower 33, or some of said forces to protect the housing 14 against undue strain.

In order to prevent the floating follower from being unduly displaced when the yoke 26 moves forwardly under the action of draft forces, miniature stop elements 37 and 38 are desirably provided and connected to the inner faces of the sills 1, so that they normally engage the front face of the follower 33 at the sides thereof and limit forward movement, so that said follower is always maintained in proper relation with respect to the associated friction wedges 21 and curved plate springs 24. In a similar way, the front follower 28 is kept from displacement, when the drawbar 25 moves forwardly, by the stop member 39 connected to the sill cover plate 40 and the stop member 41 connected to the carry iron 11.

From the foregoing description, it will be seen that under the action of draft forces, the housing 14 of the second or intermediate gear 10 is held stationary by the key 16, and the drawbar 25 pulls the yoke 26 forwardly through the connecting key 27, moving the friction elements 21 of the intermediate gear 10 into the shell or housing 14 against the resistance of the springs 24, thereby actuating only the intermediate cushioning element or draft gear 10, whereby the cushioning effect on draft is only a portion and, in the preferred embodiment, only a third, of the total capacity of the entire cushioning mechanism of the arrangement, and the travel of the coupler on draft is only a portion which, in the present preferred embodiment, is a third of the total permissible movement allowed said coupler under the action of buffing forces.

When the drawbar or coupler is subjected to buffing forces, however, it engages the front follower 28, pushing the front friction elements 21 into the front housing 14, and simultaneously moving said housing and the intermediate housing 14 rearwardly to close said intermediate housing over the associated wedges and springs, said movement being permitted by the rearward elongation of the slots 9 in the cheek plates 4, so that a full compression of the front and intermediate gears on buff is permitted as well as a

compression of the rear or inner gear 10, which is effected by simultaneous movement of the rear follower 30, the yoke 26, and the floating follower 33, resulting in inward movement of the friction 5 elements and associated springs of the inner or rearmost gear 10, the housing 14 of which is stopped by the associated backstop or center filler casting 2. It will thus be apparent that if the permissible compression of each gear 10 is 2", a 10 movement of the drawbar on buff of 6" is provided, while a movement of only 2" is provided for on draft. In other words, if the movement allowed by each cushioning device is the same, a drawbar travel on buff of three times the travel 15 on draft is provided for. It will also be apparent that although the cushioning capacity on draft is only that of the mechanism of the intermediate gear 10, yet on buff, all of the cushioning devices cooperate for absorbing the energy 20 which, as is well known, is normally greater than any draft energies to be absorbed.

Referring now to the embodiment of my invention illustrated in Figures 3 to 6, inclusive, there are shown, as in the previous embodiment, 25 draft or center sills 1^a connected by a preferably combined backstop and center filler casting 2^a and a striking casting, or combined striking casting and sill tie member 3^a. The sills are slotted for receiving draft keys for connection with associated draft rigging and, in the present embodiment, have connected thereto cheek plates 4^a which are correspondingly slotted, with the slotted portions preferably reinforced by flanges 5^a for rigidifying the edges around the slots. The 30 front slots 6^a are formed partly in rearward extensions or side portions 7^a on the striking casting, and partly in the forward portions of the cheek plates 4^a. The second or rearmost slots 9^a are formed in the cheek plates 4^a.

40 Mounted between the sills 1^a is a series of cushioning units or gears 10^a, preferably supported on carry irons 11^a and 12^a, connected to the sills in any desired manner. Each gear preferably comprises a housing or main friction element 14^a which, as in the previous embodiment, receives friction wedges or shoes 21^a and actuating curved plate springs 24^a. The front or outer pair of housings 14^a are, as in the previous embodiment, desirably formed with complementary open-ended slots 15^a cooperating to form a complete slot normally receiving the key 16^a, which functions as front stop means for the second or intermediate gear 10^a. A horizontal yoke 26^a desirably embraces the foremost and intermediate gears 10^a, with its arms extending forwardly on each side thereof slotted for receiving the key 16^a and connected to the drawbar 25^a by a front or outer horizontal draft key 27^a extending through registering slots in the yoke and drawbar, the ends of said key being received in the slots 6^a in the cheek plates 4^a and rearward extensions 7^a of the striking casting 3^a. The slots 6^a are of sufficient length to permit the key to move in both directions to stress the associated cushioning devices to the desired extent. As in the previous embodiment, front and rear followers 28^a and 30^a are employed, the front follower normally engaging stops 39^a and 41^a, and the rear follower being embraced by the yoke and disposed between the rear end thereof and the friction wedges of the intermediate gear 10^a.

45 A third or rearmost gear 10^a is employed, as 50 sion horizontal rather than vertical. In other words, the housing 14^a of the rearmost gear 10^a is disposed horizontally, so that the slot or notch 15^a extends vertically rather than horizontally, and the friction elements 21^a lie on either side of the resilient means 24^a instead of above and below. On account of this change, the floating follower 33^a, which acts as a front follower for the rearmost gear 10^a, is also disposed with its long axis horizontal rather than vertical, and a separate carry iron 42 is employed for supporting the follower 33^a and the front end of the housing 14^a for the rearmost gear 10^a. The rear portion of said housing is desirably supported on the lower flange 43 of the center filler casting 2^a, the vertical flange 32^a of said casting acting as a backstop or rear stop lug for the rear gear 10^a. As in the previous embodiment, miniature stops 37^a and 38^a are employed for the floating follower 33^a. Except as specifically described in connection with the present embodiment, the construction and operation may correspond with that of the preceding embodiment.

55 Referring now to the embodiment of my invention illustrated in Figures 7 and 8, a construction is there disclosed which is identical with that of Figures 1 and 2, or Figures 3 to 6, inclusive, inasmuch as only the front and intermediate gears 10^b are illustrated, except that the striking casting and sill tie member 3^b has its side portions 7^b extended rearwardly a greater distance than in the preceding embodiments, so as to include the front slots 6^b completely without the necessity of being supplemented by cheek plates or supplemental portions of cheek plates. 60 The second or rear slots 9^b are, as in the first embodiment shown in Figures 1 and 2, desirably formed in separate cheek plates 4^b. Except as specifically described, the present embodiment corresponds with that of either Figures 1 and 2, or Figures 3 to 6, inclusive.

65 Referring now to the embodiment of my invention illustrated in Figures 9, 10 and 11, a construction is there shown involving sills 1^c connected by a backstop and center filler casting 2^c and a combined striking casting, sill tie member and front draft lugs 3^c, said front draft lug portions being slotted, as indicated at 6^c, to receive the front draft key 27^c, which serves for connecting the drawbar or coupler stem 25^c and 70 the horizontal yoke 26^c. In the present embodiment, although a series of cushioning devices 10^c is employed, the outer two embraced by the yoke, and the inner or rearmost disposed between the yoke and backstop, yet said outermost cushioning devices here have a common housing 14^c which is open at front and rear ends to receive the friction wedges or shoes 21^c and the actuating resilient means or curved plate springs 24^c. No slots for receiving a connecting draft key are employed in connection with the housings 14^c, thereby eliminating any front stop means for the intermediate cushioning device 10^c and transferring the stopping of the front housing 14^c to the front end thereof, where the front stop lugs 39^c and 41^c at the rear of the casting 3^c act through the front follower 28^c for limiting forward movement of the front friction elements 21^c, and so act as abutment means for the front draft gear 10^c. As in the first embodiment, carry irons 11^c and 12^c are employed for supporting the front of the front housing 14^c and associated front follower 28^c, and the rear and floating

ment, the housing 14^e of the rear gear or cushioning unit 10^e is supported at its rear end on the bottom cover plate 34^e and abuts the front wall 32^e of the backstop 2^e. For relieving the rear 5 housing 14^e of overload buffing forces, rear stop lug members 35^e are desirably employed, as in the first embodiment.

From the foregoing disclosure, it will be seen that under the action of draft forces the housing 14^e of the forward and intermediate cushioning devices is moved forwardly simultaneously with the closing in of the friction elements 21^e at opposite ends as the drawbar 25^e pulls the yoke 26^e forwardly through the connecting 15 key 27^e, the front follower 28^e being stopped by the stop lug portions 39^e and 41^e on the striking casting and sill tie member 3^e, whereby the front and intermediate cushioning elements are actuated, giving a cushioning effect on draft 20 of a portion which, in the present embodiment, is two-thirds of the total capacity of the entire cushioning mechanism of the arrangement, assuming the capacities of the three cushioning devices illustrated are equal, and the travel of 25 the coupler on draft is, in the present embodiment, two-thirds of the total permissible movement allowed by said coupler under the action of buffing forces, assuming the travel of each gear or cushioning device is identical.

30 When the drawbar or coupler is subjected to buffing forces, it engages the front follower 28^e, pushing the front friction elements 21^e into the double-ended housing 14^e and simultaneously moving said housing over the associated rear 35 friction elements 21^e, so that a full compression of the front and intermediate cushioning devices is permitted on buff, as well as a compression of the rear or innermost gear 10^e, which latter compression is effected by simultaneous 40 movement of the rear follower 30^e, the yoke 26^e and the floating follower 33^e effecting inward movement of the friction elements and associated springs of the rearmost gear 10^e, the housing 14^e of which is stopped by the associated 45 backstop and center filler casting 2^e. It will thus be apparent that if the permissible compression of each gear 10^e is 2", a movement of the drawbar on buff of 6" is provided for, while a movement of only 4" is allowed on draft.

50 Referring now to the embodiment of my invention illustrated in Figures 12 and 13, a slight modification of the arrangement of Figures 9 to 11, inclusive, is there illustrated involving a slotting of the sills 1^d to the ends and a corresponding reinforcement of the side portions 7^d of the striking casting and sill tie member 3^d, so that the front slots 6^d are formed entirely in said extensions 7^d, thereby preventing the associated key 27^d from coming in contact with 55 the sill webs. As in Figures 9, 10 and 11, the combined casting 3^d has front draft lugs 39^d and 41^d which are adapted to cooperate with the associated mechanism, as described in connection with the preceding embodiment. Except 60 as specifically described in connection with the present embodiment, the same may correspond with that of said preceding movement.

Referring now to the embodiment of my invention illustrated in Figure 14, a construction 70 is there disclosed in which the lower front draft lugs are extended from sill to sill, forming a draft lug and rearwardly disposed sill tie portion 41^e on the combined striking casting and sill tie member 3^e, the upper surface of said tie member 41^e being disposed downwardly to

clear the bottom of the associated drawbar or coupler 25^e, and the front follower 28^e being extended downward a corresponding amount so as to provide the necessary bearing area therebetween. Because of the extension of the front 80 follower, the front carry iron 11^e for the housing 14^e of the front cushioning unit 10^e is correspondingly modified to provide a lower shelf portion 44 for supporting the front follower 28^e and an upper shelf portion 45 for supporting the housing 14^e. Except as specifically described in connection with the present embodiment, the same may correspond with that of Figures 9, 10 and 11.

Referring now to the embodiment of my invention illustrated in Figures 15 and 16, a construction is there disclosed corresponding with Figure 14, except that the lower front stop portion 41^f is formed as a removable key rather than an integral portion, which key is received in corresponding slots 46 in the lower portions of the sides 7^f of the combined striking casting and sill tie member 3^f, said key 41^f acting as a lower front stop for the front follower 28^f and the associated wedges 21^f of the front cushioning unit 10^f. The front follower 28^f is desirably formed T-shaped, or with extensions like the follower 28 of the first embodiment, so that it is supported from the associated yoke (not shown), thereby eliminating the necessity of a 105 separate carrier therefor. Except as specifically described and illustrated, the construction may correspond with that of Figure 14.

Referring now to the embodiment of my invention illustrated in Figure 17, a construction 110 is there disclosed which may be identical with that of Figures 9, 10 and 11, except that the yoke 26^g is extended so as to embrace all of the gears or cushioning devices 10^g with its rear end normally abutting the front face 32^g of rear 115 draft or backstop means, such as the center filler casting 2^g. The front housing 14^g is desirably double-ended, as in Figures 9, 10 and 11, to receive the friction wedges and resilient means for the front and intermediate gears, but 120 is slotted, as indicated at 15^g, to receive a supporting key 16^g functioning as front stop means for the intermediate cushioning device 10^g, and for that purpose having its ends received in slots 9^g in cheek plates 4^g connected to the associated 125 sills 1^g. As in the embodiment of Figures 9, 10 and 11, a front follower 28^g is used, and the rear and floating followers are consolidated as a single follower 33^g separating the friction elements or wedges 21^g of the intermediate and 130 rearmost cushioning units 10^g. The cushioning units and associated parts may be supported as shown in Figures 9, 10 and 11.

From the foregoing disclosure, it will be seen 135 that under the action of draft forces the housing 14^g of the outer and intermediate gears 10^g is held stationary by the key 16^g, and the drawbar (not shown) pulls the yoke 26^g forwardly, moving the rear friction elements 21^g into the front housing 14^g, while at the same time forcing 140 the rear housing 14^g over the associated friction elements 21^g, thereby actuating the intermediate and rear cushioning devices, and developing a cushioning effect of a portion, which in the present embodiment, is two-thirds, of the total capacity of the entire cushioning mechanism, with a travel, in the preferred embodiment illustrated, equivalent to two-thirds of the total permissible movement allowed the drawbar under the action 145 of buffing forces.

- When the coupler is subjected to buffing forces, it engages the front follower 28^g, pushing the front friction elements 21^g into the front of the double housing 14^g, and simultaneously moving said housing, because of the rearward extension of the slots 9^g, to close it over the friction elements 21^g at the rear, while simultaneously pushing the follower 33^g and the rear friction elements 21^g into the associated rear housing 14^g, which is stopped by the rear portion of the yoke 26^g and the backstop and center filler casting 2^g. From the foregoing disclosure, it will be seen that I have disclosed ways of combining friction draft gears so that all are effective for acting in series, as distinguished from tandem, and cushioning buffing forces, whereas only one or less than all are effective for cushioning draft forces, thereby providing a greater cushioning effect and travel when the drawbar is subjected to buffing forces than when it is subjected to draft forces.
- Although preferred embodiments of my invention have been illustrated, it will be understood that modifications may be made without departing from my invention as defined by the appended claims.
- I claim:—
1. In railway draft rigging, in combination with draft sills, a drawbar, three cushioning units disposed longitudinally of one another between said drawbar and backstop, all of said cushioning units acting in series to resist buffing movement of the drawbar, each of said cushioning units involving housing means and a plurality of friction elements cooperating therewith and urged apart by resilient means into engagement with the housing means, said backstop engaging and serving to prevent rearward movement of the housing means of the rearmost cushioning unit, means acting as a forward stop for the foremost of said cushioning units, a follower for the foremost of said cushioning units normally engaging said forward stop and engaged by the friction elements of said unit, a carry iron underlying and simultaneously supporting the follower and front end of the housing means of said unit, the housing means of the intermediate and rearmost units opening toward each other and receiving friction elements and resilient means urging said friction elements apart and into engagement with said housing means, follower means disposed between the friction elements of the intermediate cushioning unit and those of the rearmost cushioning unit, a carry iron simultaneously supporting the adjacent ends of the housing means for said intermediate and rearmost cushioning units and follower means therebetween, and yoke-acting means operatively connected to the drawbar and serving to communicate draft force to said intermediate cushioning unit, leaving one of the other cushioning units inactive during draft.
  2. In railway draft rigging, in combination with draft sills, a drawbar, three cushioning units disposed longitudinally of one another between said drawbar and backstop, all of said cushioning units acting in series to resist buffing movement of the drawbar, each of said cushioning units involving housing means and a plurality of friction elements cooperating therewith and urged apart by resilient means into engagement with the housing means, said backstop engaging and serving to prevent rearward movement of the housing means of the rearmost cushioning unit, means acting as a forward stop for the foremost of said cushioning units, the housing means of the in-
  - termediate and rearmost units opening toward each other and receiving friction elements and resilient means urging said friction elements apart and into engagement with the housing means, follower means disposed between the friction elements of the intermediate cushioning unit and those of the rearmost cushioning unit, a carry iron simultaneously supporting the adjacent ends of the housing means for said intermediate and rearmost cushioning units and follower means therebetween, and yoke-acting means operatively connected to the drawbar and serving to communicate draft force to said intermediate cushioning unit, leaving one of the other cushioning units inactive during draft.
  3. In railway draft rigging, in combination with draft sills, a backstop rigidly connected to said sills, a drawbar, a plurality of cushioning units disposed longitudinally of one another between said drawbar and said backstop and acting in series to yieldingly resist buffing movement of the drawbar, one of said cushioning units being intermediate others and each of said units involving a friction casing and a plurality of friction elements cooperating therewith, said backstop engaging and serving to prevent rearward movement of the friction casing of the rearmost cushioning unit, means acting as a forward stop for an intermediate cushioning unit, yoke-acting means operatively connected to the drawbar, disposed forwardly of said rearmost unit, and embracing and serving to communicate draft force to said intermediate cushioning unit, and carry iron means supporting the adjacent ends of the friction casings of the intermediate and rearmost units.
  4. In railway draft rigging, in combination with draft sills, a drawbar, a plurality of cushioning units disposed rearwardly of said drawbar, longitudinally of one another, said cushioning units acting in series to resist buffing movement of the drawbar, one of them being intermediate others, and each involving a plurality of friction elements relatively movable with respect to friction casing means cooperating therewith, a backstop member rigidly connecting said sills and associated with the rearmost of said cushioning units, means acting as a forward stop for the foremost of said cushioning units, yoke-acting means operatively connected to the drawbar and embracing and serving to communicate draft forces to the intermediate, and through it to the foremost of said cushioning units, another of said cushioning units being inactive when said yoke-acting means executes a draft movement, and carry iron means supporting the adjacent ends of the casing means of the intermediate and rearmost of said cushioning units.
  5. In railway draft rigging, in combination with draft sills, a backstop rigidly connecting said sills, a drawbar, a plurality of cushioning units arranged longitudinally of one another between said drawbar and backstop, said cushioning units acting in series to resist buffing movement of the drawbar and one of them being intermediate others, each of said cushioning units involving a friction casing and a plurality of friction elements cooperating therewith, said backstop serving to prevent rearward movement of the friction casing of the rearmost cushioning unit, means acting as a forward stop for the intermediate of said cushioning units and serving to prevent actuation of the foremost cushioning unit on draft, yoke-acting means operatively connected to the drawbar and serving to communi-

cate draft force to the rearmost cushioning unit, and carry iron means supporting the adjacent ends of the casings of the intermediate and rear-most cushioning units.

5 6. In a draft rigging, in combination with draft sills, a backstop rigidly connecting said sills, a drawbar, a plurality of cushioning units disposed longitudinally of one another between said drawbar and backstop, said cushioning units acting 10 in series to resist buffing movement of the drawbar and one of them being intermediate others, each of said cushioning units involving a friction casing and a plurality of friction elements cooperating therewith, said backstop engaging 15 and serving to prevent rearward movement of the friction casing of the rearmost cushioning unit, means acting as a forward stop for the foremost

of said cushioning units, yoke-acting means operatively connected to the drawbar and serving to communicate draft force to said intermediate cushioning unit, the said friction elements of the foremost cushioning unit being movable rearwardly with respect to the friction casing with which they cooperate, the friction elements of 80 said intermediate cushioning unit being movable forwardly with respect to the friction casing with which they cooperate and the friction elements of the rearmost cushioning unit being movable rearwardly with respect to the friction casing with which they cooperate, and common carrier 85 means for the adjacent ends of the casings of the intermediate and rearmost cushioning units. 90
